(57) **CLAIM**

The ornamental design for a compression calf sleeve, as shown and described.

DESCRIPTION

FIG. 1 is a perspective view of compression calf sleeve showing my new design

FIG. 2 is a front view thereof;

FIG. 3 is a back view thereof;

FIG. 4 is a left side elevational view thereof;

FIG. 5 is a right side elevational view thereof; and,

FIG. 6 is a back perspective view thereof.

The top and the bottom view of the compression calf sleeve are omitted since they are not claimed in the design.
